(57) **CLAIM**

The ornamental design for a grater, as shown and described.

DESCRIPTION

FIG. 1 is a front-right perspective view of a grater showing our new design;

FIG. 2 is a rear-right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a sectional view taken along line 9-9 of FIG. 3.

The broken lines depict portions of a grater in which the design is embodied that form no part of the claimed design.
